UNITED STATES PATENT OFFICE.

LESLIE P. GREEN, OF CHICAGO, ILLINOIS.

EXCAVATOR.

Application filed June 16, 1921. Serial No. 477,939.

To all whom it may concern:

Be it known that I, LESLIE P. GREEN, a citizen of the United States, and a resident of the city of Chicago, county of Cook, and State of Illinois, have invented certain new and useful Improvements in Excavators, of which the following is a specification.

My invention relates to improvements in excavators, and has for its object the provision of an improved construction of this character which is simple and efficient in use.

Other objects will appear hereinafter.

The invention consists in the combinations and arrangements of parts hereinafter described and claimed.

The invention will be best understood by reference to the accompanying drawings forming a part of this specification, and in which,

20 Fig. 1 is a side view of an excavator embodying the invention;

Fig. 2, an end view thereof; and

Fig. 3, a detail view of a stop member employed in the construction.

25 The preferred form of construction as illustrated in the drawings comprises a suitable supporting cable 4 which is stretched over an area to be excavated in the usual manner. A carriage 5 equipped with 30 grooved supporting wheels 6 is arranged to travel on said supporting cable over the area to be excavated in the usual manner, and a stop clamp 7 is adjustably secured to the cable 4 so as to stop the travel of said 35 carriage at any desired point in its travel on said cable.

Two triangular rocker members 8 are pivoted at 9 on carriage 5 and links 10 and 11 are pivoted, as shown, to the corners of members 8 on opposite sides of the pivots 9. An excavating bucket 12 is pivoted, as shown, to the lower ends of the links 10 and 11 and is balanced to carry its load. A draw cable 13 is connected to cause the carriage 5 and 45 the bucket 12 to traverse the area to be excavated. The cable 13 is provided with two branches 14 and 15. The branch 14 consists of two diverging cable strands leading and attached to eyes 14' on the forward edges of 50 the excavating bucket 12 as shown. The branch 15 likewise consists of two divergent

strands passing over grooved guide pulleys 16 on carriage 5 and connected with eyes 17 on the rocker members 8 as shown, the branches 15 passing close to but above the 55 pivotal axis 9.

In operation, the cable 13 is manipulated in the usual way to permit the carriage and bucket to slide down the same under gravity over the area to be excavated whereupon the 60 cable 13 is operated as a draw cable to draw the excavating bucket over the area to be excavated, filling the same with material in the usual way, said material being lifted by the upward inclination of the supporting 65 cable 4 and carried in the bucket until the stop 7 is encountered, said stop being positioned at the point where it is desired to dump the excavated material. When the stop 7 is encountered by the carriage 5, further travel of said carriage is prevented, 70 whereupon the bucket 12 will be caused to swing forwardly by the tension on cable 13. This will throw tension onto the cable strands 15 and thence onto the eyes 17 on 75 the rocker members 8. The cable strands 15 passing above the pivot points 9 will cause the rocker member 8 to rock forwardly into the dotted line position indicated in Fig. 3. This will cause links 11 to elevate the rearward end of the bucket 12 and links 10 to lower the forward end thereof, thus dumping the contents of said bucket as indicated in dotted lines in Fig. 1. When tension on cable 13 is relieved, the bucket 12 assumes 80 its normal position by the action of gravity and because it is balanced to do so, such assumption being in any event forced by contact of the bucket with the ground as the carriage 5 slides down the cable 4. Renewal 85 of the drawing force on cable 13 will repeat the operation again, filling the excavating bucket and dumping the same as above outlined. If the cable strands 14 are adjusted a little longer than indicated, the carriage 90 will be drawn along cable 4 by the tension in cable strands 15 until the stop is encountered, when the dumping action will take place as before. The added "slack" in cable strands 14 permits more free dumping movement of the bucket and thus a complete 95 upending thereof to facilitate discharge. In

either arrangement, a simple and effective excavating mechanism is provided which will carry its load to the desired point and then positively dump and discharge the same 5 at any desired point.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of 10 the appended claims.

Having described my invention, what I claim as new and desire to secure by Letters Patent is:

1. An excavator comprising a supporting cable; a carriage traveling thereon; a stop for said carriage; an excavating bucket swingingly suspended on said carriage; means on said carriage for dumping said bucket; and a draw cable operatively attached to said bucket and said dumping means, and arranged to dump said bucket forcibly by tension on said draw cable when said carriage encounters said stop, substantially as described.

2. An excavator comprising a supporting cable; a carriage traveling thereon; a stop for said carriage; an excavating bucket swingingly suspended on said carriage and balanced to carry its load; means on said carriage for dumping said bucket; and a draw cable operatively attached to said bucket and said dumping means, and arranged to dump said bucket forcibly by tension on said draw cable when said carriage encounters said stop, substantially as described.

3. An excavator comprising a supporting cable; a carriage traveling thereon; a stop for said carriage on said cable; an excavating bucket swingingly suspended on said carriage; means on said carriage for dumping said bucket; and a draw cable having two branches, one leading to said bucket and the other to said dumping means, the first of said branches serving to draw said carriage and bucket along said supporting cable, and the other branch serving to dump said bucket forcibly by tension on said draw cable when said carriage encounters said stop, substantially as described.

4. An excavator comprising a supporting cable; a carriage traveling thereon; a stop for said carriage on said cable; an excavating bucket swingingly suspended on said carriage and balanced to carry its load; means on said carriage for dumping said bucket; and a draw cable having two branches, one leading to said bucket and the other to said dumping means, the first of said branches serving to draw said carriage

and bucket along said supporting cable, and the other branch serving to dump said bucket forcibly by tension on said draw cable when said carriage encounters said stop, substantially as described.

5. An excavator comprising a supporting cable; a carriage traveling thereon; a stop for said carriage; a rocker member pivotally mounted on said carriage; supporting links pivoted to said rocker member; an excavating bucket pivotally carried by said links; said bucket being arranged to be dumped by rocking of said rocker member; and a draw cable operatively connected with said bucket and with said dumping means, substantially as described.

6. An excavator comprising a supporting cable; a carriage traveling thereon; a stop for said carriage on said cable; a rocker member pivotally mounted on said carriage; depending supporting links pivoted on said rocker on opposite sides of the pivot thereof; an excavating bucket pivotally suspended on said links and balanced to carry its load, and arranged to be dumped upon rocking of said rocker member on said carriage; and a draw cable having two branches, one leading to said bucket and the other to said dumping means, substantially as described.

7. An excavator comprising a traveling carriage; an excavating bucket swingingly mounted on said carriage; a draw cable having two branches, one branch leading to said bucket and the other to said carriage; and means on said carriage, operable by the shifting of tension onto the cable branch leading to said carriage for dumping said bucket, substantially as described.

8. An excavator comprising a supporting cable; a carriage traveling thereon; a stop for said carriage on said cable; triangular rocker members pivoted on said carriage; supporting links pivoted to said rocker member on opposite sides of the pivot thereof; an excavating bucket suspended on said links and balanced to carry its load; and a draw cable having two branches, one branch leading to said bucket and the other to said rocker member, and adapted and arranged to rock said rocker member when tension is shifted thereon, substantially as described.

9. An excavator comprising a supporting cable; a carriage traveling thereon; a rocker member on said carriage; an excavating bucket; a support for one end of said bucket connected with said rocker member; a support for the other end of said bucket connected with said rocker member; and means for rocking said rocker member, substantially as described.

10. An excavator comprising a supporting cable; a carriage traveling thereon; a stop for said carriage on said cable; a rocker member pivoted on said carriage; an excavating bucket swingingly suspended on said

rocker member on opposite sides of the pivot thereof; and a draw cable having two branches, one leading to said bucket and the other to said rocker member and adapted to rock said rocker member upon stopping of said carriage, substantially as described.

In testimony whereof I have signed my

name to this specification in the presence of two subscribing witnesses.

LESLIE P. GREEN.
